UNITED STATES PATENT OFFICE.

WILLIAM J. DONNELLY, OF MARYSVILLE, MONTANA.

SAFETY-RAZOR BLADE AND HOLDER.

1,217,288.

Specification of Letters Patent. Patented Feb. 27, 1917.

Application filed July 20, 1915. Serial No. 40,971.

To all whom it may concern:

Be it known that I, WILLIAM J. DONNELLY, a citizen of the United States, residing at Marysville, in the county of Lewis and Clark, State of Montana, have invented certain new and useful Improvements in Safety-Razor Blades and Holders; and I do hereby declare the following to be a full, clear, and exact description of the invention, such as will enable others skilled in the art to which it appertains to make and use the same.

This invention relates to improvements in safety razor blades and holders therefor. One object of the invention is to provide a simple and effective device wherein a safety razor blade will be firmly held without danger of accidental displacement.

Another object is to provide a device of this character in which the guard and razor blade can be quickly and easily attached to or removed from the holder.

Other objects and advantages will be apparent from the following description when taken in connection with the accompanying drawing.

In the drawing:

Figure 1 is an elevation of my improved safety razor,

Fig. 2 is an elevation from the opposite side of that of Fig. 1,

Fig. 3 is an edge view,

Fig. 4 is a longitudinal section on the line 4—4 of Fig. 1,

Fig. 5 is an enlarged fragmentary view on the line 5—5 of Fig. 4, and

Fig. 6 is a section on the line 6—6 of Fig. 5.

Referring particularly to the accompanying drawing, 10 represents the guard which consists of an elongated metallic plate having the curved teeth 11 formed on each of its longitudinal sides. A holder 12 is provided with a shank 13 adapted to be screwed into a hand grip 14. The outer portion of the holder is provided with a flat face 15 against which the guard 10 is placed. On the inner end of the holder, and extending longitudinally in spaced relation to the flat face thereof is a lip 16. Between this lip and the flat face is formed a lug 17 of a width less than the width of the lip. One end of the guard is formed with a central notch 18 which receives the said lug snugly therein, said end being disposed between the lip and the flat face of the holder. On the

opposite face, and on the outer end of the holder is formed a recess 19, the inner wall of which inclines inwardly toward the flat face as shown at 20. The adjacent end of the guard is formed with a tongue 21 bent rearwardly and engaged over the end of the holder and in the notch 19. The razor blade 22 is disposed between the guard and the flat face of the holder, and has in one end a notch 23 which also receives the lug 17, while in the other end there is formed a notch 24 receiving a portion of the tongue 21 therethrough. It will be noted that the free end of the tongue inclines inwardly toward the face of the guard, so that it will snap into the recess 19 and firmly hold the guard and blade in position on the holder.

Particular attention is directed to the fact that by reason of the notches of the blade 22 and of the guard, together with the tongue 21 and the lug 17, the guard and blade are thus firmly held against any lateral movement in the holder. The tongue and lip hold the blade and guard against movement in the other direction on the holder, while the tongue alone prevents longitudinal movement accidentally.

What is claimed is:

1. A safety razor comprising a handle, an extension on the handle provided with a longitudinal lip near the base thereof, a lug formed between the lip and extension, a razor blade having notches in its opposite ends, one end of said blade being disposed between the lip and extension with the notch receiving the said lug, the outer end of the extension having an inwardly inclined recess, and a guard having a notch in one end receiving the said lug and a resilient tongue on the opposite end thereof for engagement in said recess.

2. A safety razor comprising a stem having a flat face, a longitudinal lip formed on the inner end thereof and spaced from the flat face, a lug between the lip and flat face, a razor blade disposed against the flat face with one end between the lip and flat face, a guard disposed against the blade with one end between the lip and flat face, said ends of the guard and blade being formed with registering notches receiving said lug, the other end of the stem having a recess in its other face, the inner wall of said recess inclining inward longitudinally and a resilient tongue carried by the outer end of

the guard for embracing the outer end of the blade and stem and engaging in said recess.

3. A safety razor comprising a stem having a flat face, a longitudinal lip formed on the inner end thereof and spaced from and overhanging the flat face, a lug between the lip and flat face, a razor blade disposed against the flat face with one end between the lip and flat face, a guard disposed against the blade with one end between the lip and flat face, said ends of the guard and blade being formed with registering notches receiving said lug, the remaining end of the stem being provided with a notch registering with the notches in the guard and

blade and having a recess extending inwardly from the notch, said recess having its inner wall inclined downwardly from the notch toward the body of the stem, and a resilient tongue carried by the outer end of the guard and having its end inclined downwardly, said tongue being adapted to engage the outer end of the blade and to lie in said recess.

20 In testimony whereof, I affix my signature, in the presence of two witnesses.

25 WILLIAM J. DONNELLY.
